(57) **CLAIM**

The ornamental design for a model vehicle bellcrank and draglink assembly as shown and described.

DESCRIPTION

FIG. 1 is an upper, left, front perspective view of a model vehicle bellcrank and draglink assembly showing our new design;

FIG. 2 is an upper, right, rear perspective view thereof;

FIG. 3 is a lower, right, front perspective view thereof;

FIG. 4 is a lower, left, rear perspective view thereof;

FIG. 5 is a front elevation view thereof;

FIG. 6 is a rear elevation view thereof;

FIG. 7 is an upper plan view thereof;

FIG. 8 is a lower plan view thereof;

FIG. 9 is a right-side elevation view thereof; and,

FIG. 10 is a left-side elevation view of the model vehicle bellcrank and draglink assembly.

In the drawings, the broken lines illustrate portions of the model vehicle bellcrank and draglink assembly that form no part of the claimed design.

1 Claim, 7 Drawing Sheets
